UNITED STATES PATENT OFFICE

GEORGE C. CHASE, OF SOUTH ORANGE, NEW JERSEY, ASSIGNOR TO MONROE CALCULATING MACHINE COMPANY, OF ORANGE, NEW JERSEY, A CORPORATION OF DELAWARE

CALCULATING MACHINE

Application filed March 13, 1929. Serial No. 346,686.

The invention relates to calculating machines, and more particularly to mechanism for facilitating the automatic calculation of problems in multiplication and in division.

5 According to the invention, means are provided for starting an additive registration on the numeral wheels of the machine and for thereafter automatically controlling the stopping and/or carriage shifting and reversing 10 devices, to determine the extent of the registration, by an over-carry action in the numeral wheels.

The invention consists in the novel construction and combination of parts, as set 15 forth in the appended claims. The invention forms a modification of the mechanism of the known Monroe calculating machine, disclosed in essential particulars in applicant's United States Patent Number 1,566,650, issued De- 20 cember 22, 1925, and in co-pending applica- tions Number 79,811 filed January 7, 1926, entitled "Automatic control for calculating machines" and Number 213,637, filed August 17, 1927, entitled "Division stop mechanism 25 for calculators", in combination with other devices disclosed in the co-pending applica- tion of E. F. Britten, Jr., Number 337,073, filed February 2, 1929, and entitled "Regis- tering mechanism".

30 In these machines division may be accom- plished by use of automatic control devices by either of the following methods:

The dividend being registered as a positive quantity in the numeral wheels, and the 35 divisor being set in the keyboard, the automatic control lever is thrown into operative position, whereupon the actuating mechanism of the machine is set in operation by connection with an electric motor, the direc- 40 tion of rotation of the actuators being such as to cause subtractive registration upon the numeral wheels. Counting wheels are pro- vided for registering the number of rotations of the actuators, this registration indi- 45 cating the quotient at the end of the opera- tion. When a subtractive registration has been continued until one more subtraction has been made than indicated by the correct quo- tient figure, the actuating mechanism is auto- 50 matically reversed and one corrective additive

rotation is made, whereupon the carriage in which the numeral wheels are mounted is shifted one decimal order toward the left and the operation is automatically repeated to determine the next quotient figure.

55 Division may also be accomplished by the following modification of this method; the counting wheels being provided with tens carry mechanism, according, for instance, to the disclosure of application Number 337,073:

60 The dividend is registered in the numeral wheels as a negative quantity, that is to say, the complement of the dividend is registered, for which purpose the dividend is set up as a positive amount on the keyboard and reg- 65 istered negatively by operation of the sub- tract key. The divisor being now set in the keyboard, the add key is held depressed until the machine has registered the required or one more than the required quotient figure, 70 whereupon the actuating mechanism will be automatically brought to rest. The numeral wheel carriage is now shifted one decimal order to the left and the automatic control lever is thrown into operative position, where- 75 upon the subtractive rotation of the actuators will first make any necessary correction of the first quotient figure, and thereafter the machine will complete the division problem in the manner above described.

80 The principle of operation of this last de- scribed method of performing division pro- vides means whereby automatic multiplication 85 may be performed in accordance with a pre-set multiplicand and a pre-set multiplier of any number of figures. In carrying out this operation, the complement of the mul- tiplier is registered in the numeral wheels aligned with the left-hand portion of the keyboard and the numeral "1" is set in the 90 extreme left-hand column of the keyboard to represent a divisor, the multiplicand being set up at the right-hand portion of the keyboard. Upon operation by the add key and control lever, as described for the second 95 method of division, the multiplier will be divided by one and the correct product will be registered in the numeral wheels aligning with the right-hand portion of the keyboard. In other words, according to this method, the 100

multiplier is first subtracted from zero and thereafter added back, a unit at a time, whereby the multiplier value is enabled to control the number of rotations of the actuators.

5 By use of the present invention, the above described method of performing multiplication may be performed without necessitating the use of two motor keys to register the product in accordance with the first left-hand and of the lower order figures of the multiplier. It will also be apparent that, 10 while multiplication has been simplified, division may still be performed without any additional operation, by means of the second method above described.

15 In the accompanying drawings, illustrating the invention, Fig. 1 is a fragmentary left side elevation showing a multiplication and division control lever, with the associated 20 parts of the control mechanism. Fig. 2 is a similar view showing the transmission, carriage shifting and other cooperating devices. Fig. 3 is a fragmentary front elevation of the carriage shifting devices.

25 In these drawings, illustrating the invention as applied to the structure of the hereinbefore named disclosures, the control lever is shown as made in two parts, the main portion 201 and a handle portion 318, mounted 30 on a common fulcrum 202 of the framing and connected by a pin and slot means 300. The reversing clutch lever 111 carries at the forward end thereof a pawl 319, pivoted at 205 and having a suitable spring, acting to hold 35 the pawl in contact with stop 207. A suitable click latch locates the control lever 201 under spring tension either in retracted or in operative position. The control lever 201 is provided at its lower end with a pin 208 which 40 contacts with pawl 319 during the setting movement of the control lever to adjust said reversing clutch lever from neutral to add position. The action of the clutching and 45 reversing transmission mechanism 106 controlled by lever 111 is fully shown in Patent 1,566,650 hereinbefore referred to, and, since the specific details of this mechanism form no part of the present invention, they are not illustrated herein. Control lever 201 also 50 acts, through a bar 217 to engage a clutch hub 61 in the carriage shifting train with a clutch member on the shifting shaft 46.

55 The machine having been put in operation, will continue to run in an additive direction until a transitional carry occurs, under the conditions described in the patent above named, at which time the full-cycle stop mechanism, illustrated in said patent, will operate to bring reversing clutch lever 111 60 into neutral position. Briefly, this action occurs through the operation of a pin of numeral wheel 13, trigger 31, the falling of element 25 of arm 24 into the path of rock arm 22, and the action of pin 145 of arm 24 65 upon a cam face of lever 111.

The rebound, or spring urged reverse movement of the parts; including actuator shaft 4, crank arm 20 thereon, link 21, and rock arm 22, from the position in which further forward rotation of shaft 4 is prevented; 70 serves to move the reversing clutch lever 111 from neutral to subtractive position by the following means:

A pivoted, slidably adjustable tooth 209 is 75 carried upon the forward arm of reversing clutch lever 111, and is provided with a stud 211 adapted to be engaged by an edge portion 212 of control lever 201, the movement of said lever to operating position acting to move tooth 209 forwardly, against the tension of spring 210. Upon the side of reversing clutch lever 111 opposite tooth 209 is provided a pawl 213, the free end of which is adapted to fall behind a pin 211 and latch tooth 209 in forward position when so moved 80 by the control lever.

The rebound of the mechanism referred to will cause tooth 220 of the link 21 of the stop mechanism to sweep upward and engage the forward end of the projecting tooth 209 and move the reversing clutch lever into subtractive position. Similarly, upon the operation of the transitional carry at the end of a subtractive rotation, arm 20 passing through its normal dead-center position on the rebound, tooth 220 of link 21 will sweep downward, engaging tooth 209 and moving the reversing clutch lever into additive position. These reversal operations, together with the automatic shifting of the numeral wheel carriage, thru the lever train 47, 52, 54, 55, cam 60 with its clutch hub 61, shaft 46 and crank pin 64, fully described in the before named applications, will continue automatically until the carriage has reached its extreme left-hand position or until the lever 201 is manually returned to inoperative position, whereupon the final quotient figure will be correctly registered and the machine 100 automatically brought to rest. 105

110 It will be apparent that the machine will stop after the correct multiplier is registered even though no carriage movement occurs, as when the operation is started with the carriage in extreme left-hand position or in case the operation is started by a forward and retractive movement of the control lever. This will be true whether there are one or more figures in the multiplier, as long as the numeral "1" set up in the keyboard is placed in alignment with the left-hand figure of the negatively registered multiplier. In the case of a multiplier of more than one figure, this last named method of operation will require the full number of rotations of the actuators called for by such multiplier (twelve rotations to multiply by twelve, etc.), since there is no shifting of the carriage to equal a multiplication by ten. 115

120 The above method of operation would be 130

useful in machines not equipped with shiftable numeral wheel carriages and in machines wherein certain operations must be performed without shifting the carriage.

5 This latter condition is encountered in the machine disclosed in my United States Patent 1,468,992, issued September 25, 1923, and entitled "Calculating machine", wherein British currency or other fractional problems are solved in a fixed position of the carriage.

10 The application of the present invention to the machine constructed in accordance with this patent would enable multiplication to be performed in an automatic manner where one

15 of the factors includes fractional values or values different portions of which have different denominators.

I claim:

- 20 1. In a power driven calculating machine, having a product-dividend register comprising reversible numeral wheels, and actuators therefor; operation control means including a member manually settable to determine rotation of said numeral wheels in an additive direction and to initiate operation of the actuators, and means controlled by the settable means and by the numeral wheels and adapted to automatically reverse the direction of rotation of said wheels.
- 25 2. In a power driven calculating machine having a transversely shiftable carriage, a product-dividend register comprising reversible numeral wheels mounted in said carriage, and actuators therefor; operation control means including a member manually settable to determine rotation of said numeral wheels in an additive direction and to initiate operation of the actuators, and means controlled by the settable means and by the numeral
- 30 wheels and adapted to shift the numeral wheel carriage and to automatically reverse the direction of rotation of said wheels.

In testimony whereof, I affix my signature.

GEORGE C. CHASE.
